UNITED STATES PATENT OFFICE.

ARTHUR W. THOMPSON, OF OTTAWA, ONTARIO, CANADA.

COMBINED PUMP AND DISTRIBUTOR.

Application filed April 14, 1922. Serial No. 552,744.

To all whom it may concern:

Be it known that I, ARTHUR W. THOMPSON, a citizen of the Dominion of Canada, and resident of the city of Ottawa, in the 5 Province of Ontario, Dominion of Canada, have invented certain new and useful Improvements in Combined Pumps and Distributors, of which the following is a specification.

10 My invention may be used as a pump or as a liquid distributor, or as a combined pump and distributor, and acts to take a liquid from a source of supply and force separate measured charges through a plurality of separate outlets or delivery conduits in succession.

15 Although my invention may be used for pumping or distributing any liquid, it is intended primarily for use in connection with 20 a multiple cylinder internal combustion engine of the Diesel or other type in which the separate successive fuel charges are pumped or forced directly into the engine cylinder. These several conduits may extend to the 25 separate cylinders and the number and distribution of these outlets and the speed of rotation of the pump may be such that the fuel charges are delivered to the cylinders in the proper order and at the proper instant in the cycle of operation of each cylinder.

30 In my improved construction I provide a casing having one or more outlets from a chamber formed by the casing and a pair 35 of members within the casing and rotatable about the axis of the latter. These members have a relative movement circumferentially so that the chamber or space between the opposing ends of the members forms a pump 40 chamber of varying capacity which may communicate with an outlet or outlets of the casing during the rotation of the two members forming the rotor. The relative movement of the members is so controlled that 45 their opposing ends or surfaces are brought together when opposite each discharge or outlet port, and separated between discharge ports to take in liquid so that the relative movement of the members effects a pumping 50 action. This pumping action is so controlled as to take place a plurality of times during each rotation, and at points properly located in respect to the several separate outlets.

As a further important feature of my invention, I provide a yielding connection between the two members, which normally tends to hold the members in such predetermined relationship as to make the pump chamber of one limiting capacity, for instance maximum size, and I provide stop 60 mechanism for overcoming the action of the yielding connection at the desired points in the cycle of rotation and effect such relative movement of the members as will tend to bring the pumping chamber to its opposite 65 limiting capacity, for instance minimum size. The stop mechanism is preferably a yielding one, so that its action is automatically overcome when the resistance reaches a predetermined point. If the yielding connection between the members acts to separate them, and enlarge the pump chamber for a suction stroke, the stop mechanism may momentarily retard one member in respect to the other to effect the discharge or delivery 70 stroke. By varying the resistance which the stop mechanism offers to the free rotation of the members, the pumping action may be controlled to vary the quantity of liquid delivered, and thus means for controlling the 75 yielding stop mechanism may serve as a throttle for controlling the fuel delivery to the engine and controlling the speed and power of the engine.

I have illustrated merely one embodiment 85 of my invention in the accompanying drawings in which—

Fig. 1 is a central longitudinal section on the line 1—1 of Fig. 3.

Figs. 2 and 3 are transverse sections on the 90 lines 2—2 and 3—3 respectively of Fig. 1,

Figs. 4 and 5 are sections similar to a portion of Fig. 3, but showing the parts in different positions, and

Figs. 6 and 7 are perspective views of the 95 separate parts of the rotor.

In the form illustrated, I provide a casing 10 having a cylindrical chamber within which is mounted the rotor. The casing has an inlet 11 from a suitable source of liquid supply, and an annular row of outlet ports 12 in the periphery thereof, and communicating with liquid delivery pipes 13 which may lead to the separate cylinders of a multiple cylinder internal combustion engine. 100 The number of these outlet ports and deliv-

ery pipes may of course be varied in accordance with the particular purpose for which the device is used, or in accordance with the number of cylinders, if the device 5 be used as a combined fuel pump and distributor for an engine. The outlet ports may be formed in a liner member 14 which may be fixed to the casing within the chamber.

10 The rotor includes a pair of members rotatable about a common axis, and having limited relative rotary movement. One of these members is shown as including a disk portion 15 of such diameter as to closely fit 15 the interior of a chamber at one end of the liner 14. The disk is secured to or integral with a sleeve 16, which latter is keyed to a shaft 17 so that the sleeve and disk may have limited endwise movement on the shaft, 20 and toward and from the end of the liner 14. Within the chamber at the side of the disk opposite to the liner is a supply chamber 18 with which the supply pipe 11 communicates. The return flow of liquid from 25 the chamber to the supply pipe 11 may be prevented by a check valve 19 and the chamber itself may be filled, for instance for starting, through a separate inlet normally closed by a plug 20, a priming cock or other 30 suitable form of closure.

The disk 15 on the side thereof opposite to the chamber 18 has a centrally disposed boss 21 having a circular peripheral wall spaced from the liner member 14.

35 The disk 15 also carries a ring section 22 extending radially from the periphery of the hub or boss 21 to the liner 14, and extending circumferentially along only a limited portion of the space between the hub 40 or boss 21 and liner 14. The disk 15 has a pair of ports 23 and 24 therethrough adjacent to opposite ends of the ring section 22. The function and operation of these ports will be more fully pointed out hereinafter. 45 Although the disk 15, boss 21 and ring section 22 may be made integral as indicated in Figs. 1, 3, 4 and 5, economy in manufacturing operation is accomplished by making the ring section 22 of a separate piece 50 rigidly secured in place.

The other member of the rotor includes a disk 25 slightly smaller than the disk 15, and mounted to closely fit within the liner 14 and against one end of the main chamber of the 55 casing. This disk is rigidly connected to or integral with a sleeve 26 which is rotatable on the shaft 17. The disk 25 cooperates with the disk 15, the liner 14 and the hub or boss 21 to form an annular chamber, 60 a portion of which is filled by the ring section 22 which corresponds in cross-section to that of the annular chamber. Another portion of this annular chamber is filled by a ring section 27 corresponding in shape to 65 the ring section 22, but these ring sections

are of such length that they do not completely fill the annular chamber circumferentially and thus they permit of a limited relative rotation of the two disks carrying the ring sections. This relative rotation 70 permits of the forming of two chambers 28 and 29 of variable capacity between the two pairs of opposed ends of the ring sections. One of these chambers, for instance the chamber 28, serves as the pumping chamber 75 as hereinafter pointed out. It will be noted that as the two members rotate, this pumping chamber will come into communication with the several outlet ports 12 in succession, and that it may communicate with the supply chamber 18 through the port 23.

One of the two members of the rotor, for instance the member including the disk 15, is provided with means whereby it may be positively rotated in proper timed relationship to the engine crank shaft. As shown, the shaft 17 has a gear or sprocket wheel 30 loose thereon, and provided with a one-way acting, one-tooth clutch connection 31 to the sleeve 16. The clutch members are held in 90 operative engagement by a coil spring 32 so that the pump mechanism will not be turned backward upon a reversal of the direction of rotation of the gear 30; the gear and sleeve can operatively interlock in only 95 one predetermined position, and the sleeve and shaft may be positively rotated in a forward direction when the engine and gear 30 are at rest.

During normal operation, the disk 15 100 with its ring section 22 will thus be positively driven at a substantially uniform rate. In order to effect the variable speed movement of the other member of the rotor to give the pumping and distributing action, I provide yielding connections between the members and a yielding stop for one of them. As shown, the shaft 17 has a fly-wheel 33 rigidly secured thereto, and the sleeve 26 of the disk 25 has a flange or 105 wheel 34 rigid therewith. The yielding connection between the two members of the rotor is preferably between the wheels 33 and 34, as one of these is secured to one member of the rotor and the other to the 110 other member of the rotor. The yielding connection as illustrated includes a pin 35 carried by the fly-wheel 33, a pin 36 carried by the fly-wheel 34, and a spring 37 engaging with these two pins and tending to 115 separate them to the maximum distance. This maximum distance is controlled by the spacing between the ends of the ring sections 22 and 27, and the relative permissible rotation of the two members of the rotor. 120 The spring tends to keep the two members in such relative position that the chamber 28 is of the maximum capacity and the chamber 29 of the minimum or negligible capacity.

Stop mechanism is provided for intermittently offering such resistance to the rotation of the wheel 34 as will in effect stop the ring section 27, and permit the ring section 22 to catch up with it, and reduce the capacity of the chamber 28 and thereby discharge liquid therefrom. In the stop mechanism illustrated the flange or wheel 34 is in the form of a star wheel with projections or arms 38 corresponding in number and spacing to the discharge ports 12 of the pump. A yielding member is mounted in the path of these projections or arms, so that as the projection engages the member, the star wheel is momentarily stopped until the offered resistance is overcome. The yielding member is shown as a spring 39 carried by a bracket 40, and having a free end in the path of movement of the extremities of the arms 38. The pressure of the spring may be varied by means of an adjusting screw 41. Obviously the spring 39 which constitutes the yielding stop must offer such resistance as will overcome the action of the spring 37 and the excess must be sufficient to overcome the back pressure in the several liquid discharge pipes 13. The fly-wheel 33 is provided with means whereby it may be readily turned by hand in case it is desired to operate the pump when the engine is at rest. This means may include a suitable handle 42 normally held in a recess in the fly-wheel by the action of a spring, but adapted to be pulled out so that it may be grasped in turning the fly-wheel.

In the operation of my improved device the member of the rotor which includes the ring section 22 is positively driven at the proper speed through the gear 30. The spring 37 tends to keep the ring section 27 rotated to the limiting forward position so that the chamber 28 is of the maximum limiting capacity, as shown in Fig. 3. This chamber is in open communication with the supply chamber 18 through the port 23. The instant that the end of the ring section 27 passes a port, as shown in Fig. 3, one of the arms 38 of the star wheel engages the yielding stop 39, and the ring section 27 is thus brought to rest. The ring section 22 which is positively driven, continues rotation until it approaches or reaches the position shown in Fig. 4. During this movement, the port 23 moves behind and is closed by the ring section 27, so as to prevent further escape of liquid through this port, and the further positive rotation of the ring section 22 further reduces the capacity of the chamber 28 and forces liquid therefrom through the discharge port 12 and delivery pipe 13. When the ends of the two sections come together, or when the pressure resisting the bringing of them together is sufficient to overcome the action of the spring stop 39, the arm of the star wheel will be released and the spring 37 will instantly advance the ring section 27 and open up the chamber 28 to the maximum capacity, thus taking in a fresh supply of liquid through the port 23 preparatory to discharging it when the next outlet port is reached. If the pump work at full capacity the ring section 22 will cover the outlet port 12, as shown in Fig. 4, before the arm of the star wheel is finally released and the ring section 27 jumps forward. Thus the closing up of the chamber 28 takes place while this chamber is in communication with an outlet port, and the opening does not take place until after the chamber is out of communication with the outlet port. The port 23 may be placed at any desired distance from the adjacent end of the ring section 22, and this distance will determine the maximum amount of liquid which can be discharged by the pump through each outlet port. The port 24 in the disk 15 is made closely adjacent to its corresponding end of the ring section 22, so that the increase or decrease in the capacity of the chamber 29 which takes place simultaneously with a decrease or increase in the capacity of the chamber 28 merely effects a free outflow or inflow of liquid through the port 24. The length of the ring section 22 is such that the opening up and closing of the chamber 29 takes place along a section of the annular path between two adjacent ports so that the chamber 29 is of minimum or negligible capacity each time it passes a discharge port 12.

The back pressure in the discharge pipes offers a resistance to the pumping of liquid into said pipes and therefore tends to resist the closing up of the pumping chamber 28. The greater the back pressure the quicker will the star wheel be released, and the smaller will be the quantity of liquid forced into the pipe by the pump. By adjusting the screw 41 the resistance offered by the spring stop 39 may be varied at will so that the resistance offered by the back pressure of the liquid and the pressure of the spring 37 will not be overcome until the desired quantity of liquid has been forced into the discharge pipe. By adjusting the screw 41 to vary this resistance, the quantity of liquid discharged may thus be readily controlled and the screw 41 may serve as the throttle for controlling the fuel charge, speed and power of the engine. When it is desired to operate the pump by hand this may be readily done by means of the fly wheel 33 and handle 42. During hand operation the action of the pump will be exactly the same as during normal operation, except that the clutch 31 slips and the gear 30 remains at rest. It will be noted that if for any reason the pressure in the pumping chamber 28 becomes unduly excessive, this pressure may be relieved by the endwise movement of the

disk 15 along the shaft 17 from the position indicated in Fig. 1, and against the action of the spring 32.

In the form illustrated I rely upon the relative movement of the two ring sections 22 and 27 to cover and uncover the port 23 to permit the flow of liquid into the pump chamber 28. This is desirable from the standpoint of simplicity of design and economy of manufacture, but it will be evident that this port may be placed closely adjacent to the end of the ring section 22 and be controlled by any suitable form of inwardly opening check valve.

15. The hub or boss 21 might be carried by or form a part of either member of the rotor, but it is preferable that it be on the driven member of the rotor in order that the spring actuated member be as light in weight as possible. The minimum mass is desirable for the spring actuated member of the rotor in order that it may be suddenly stopped by the spring 39 and in order that it may accelerate rapidly and open up the chamber 28 after being released from the spring 39 and before the pump chamber reaches the next discharge port.

Having thus described my invention, what I claim as new and desire to secure by Letters Patent is:—

30. 1. A pump including a pair of rotatable relatively movable members cooperating to form a chamber of varying capacity, driving means for one of said members, yielding connections between said members tending to maintain the chamber at one limit of capacity and means for overcoming the action of said yielding means and effecting a relative movement of said members and a change in the capacity of said chamber at a predetermined point in the revolution of said members.

35. 2. A pump including a pair of rotatable relatively movable members having spaced portions forming a pump chamber, driving means for one member, yielding connections between said members tending to hold said portions spaced to the maximum extent, and means for resisting the free rotation of the other member at a predetermined point in the revolution of said members to effect a relative movement of said members.

40. 3. A pump including a pair of rotatable relatively movable members having spaced portions forming a pump chamber, driving means for one member, yielding connections between said members tending to hold said portions spaced to the maximum extent, and means for resisting the free rotation of the other member at a plurality of spaced points in each revolution of said member.

45. 4. A pump including a driven rotor member having a pump chamber, a piston member carried by said rotor member in said chamber, resilient connections between said

members tending to move said piston member toward one end of said chamber, and a yielding stop for effecting a movement of said piston member toward the opposite end of the chamber at a predetermined point 70 in the revolution of said members.

5. A combined pump and distributor including a casing having an annular row of discharge ports, a pair of rotatable relatively movable members within said casing, and having ports spaced to form a pump chamber, and means for effecting a relative movement of said members to decrease the capacity of said chamber each time it is in communication with a discharge port and increase the capacity of the chamber between successive discharge ports. 75

6. A device of the class described, including a casing having a liquid chamber, a rotor within said casing and including two relatively movable members normally spaced to form a pump chamber, one of said members having an inlet port to said pump chamber from said liquid chamber and the wall of said casing having an outlet port with which said chamber communicates once during each revolution of the rotor, and means for effecting relative movement of said members during rotation. 80

7. A device of the class described, including a casing having a liquid chamber, a rotor within said casing and including two relatively movable members normally spaced to form a pump chamber, one of said members having an inlet port to said pump chamber from said liquid chamber and the wall of said casing having an annular row of outlet ports at spaced points about the axis, and with which said pump chamber communicates in succession, and means for effecting relative movement of said members during rotation to effect pumping action. 90

8. A device of the class described, including a casing having a liquid chamber, a rotor within said casing and including two relatively movable members normally spaced to form a pump chamber, an inlet port to said pump chamber from said liquid chamber, an outlet port with which said pump chamber communicates once during each revolution of the rotor, and means for effecting relative movement of said members with said pump chamber in communication with said outlet port. 100

9. A device of the class described, including a casing having a liquid chamber, a rotor within said casing and including two relatively movable members normally spaced to form a pump chamber, an inlet port to said pump chamber from said liquid chamber and an outlet port with which said chamber communicates once during each revolution of the rotor, means for driving one of said members at substantially uniform speed, stop mechanism for intermit- 105

tently retarding the other member, and connections between said members for advancing the last mentioned member in respect to the first when released from the action of 5 said stop.

10. A device of the class described, including a casing having a liquid chamber, a rotor within said casing and including two relatively movable members normally spaced to form a pump chamber, one of said members having an inlet port to said pump chamber from said liquid chamber and the wall of said casing having an annular row of outlet ports at spaced points about the 15 axis, and with which said pump chamber communicates in succession, means for rotating one of said members at substantially uniform speed, stop mechanism for intermittently retarding the other member a plurality of times during each revolution and when the pump chamber is in communication with a corresponding outlet port, and means for advancing said second mentioned member to take in liquid through said inlet 20 port while said pump chamber is between successive outlet ports.

11. A device of the class described, including a casing, a rotor within said casing and including two relatively movable members normally spaced to form a pump chamber, having an inlet port and an annular row of outlet ports at spaced points about the axis, and with which said pump chamber communicates in succession, means for driving 30 one of said members at substantially uniform speed, spring connections between said members normally tending to hold them in predetermined relative position with the pump chamber at maximum capacity, and a yielding stop for retarding said last mentioned member a plurality of times during each revolution to effect the discharge of liquid from said pump chamber when the pump chamber is in communication with each of 40 the several outlet ports.

12. A device of the class described, including a casing having an annular row of discharge ports, a disk in said casing spaced from one end thereof to form a liquid supply chamber out of direct communication with said discharge ports, a member at the opposite side of said disk and movable in respect thereto, to form with said casing and said disk a pump chamber communicating with said discharge ports in succession, said disk having a port for admitting liquid from said supply chamber to said pump chamber.

13. A device of the class described, including a casing having an annular row of discharge ports, a disk in said casing spaced from one end thereof to form a liquid supply chamber out of direct communication with said discharge ports, a member at the opposite side of said disk and movable in

respect thereto, to form with said casing and said disk a pump chamber communicating with said discharge ports in succession, said disk having a port for admitting liquid from said supply chamber to said pump 70 chamber, and said port being controlled by the relative movement of said disk and said member.

14. A device of the class described, including a casing having a discharge port, a rotatable disk in said casing spaced from one end of the casing to form a liquid supply chamber on the side of the disk opposite to said port, said disk having a port therethrough and a member within said 80 casing rotatable with said disk and movable in respect thereto to control the port in said disk and to effect the discharge of liquid through said outlet port.

15. A device of the class described, including a casing having a discharge port, a rotatable disk in said casing spaced from one end of the casing to form a liquid supply chamber on the side of the disk opposite to said port, said disk having a port therethrough and a member within said casing rotatable with said disk and movable in respect thereto to effect the discharge of liquid through said outlet port.

16. A device of the class described, including a casing having an inlet port and an outlet port, a disk rotatably mounted in said casing and forming a partition between said ports, and having a port therethrough and a member within said member and rotatable about the same axis as said disk and having limited relative circumferential movement in respect thereto, said member and said disk having spaced parts to form a pump chamber communicating with the 100 port in said disk, and intermittently communicating with said discharge port.

17. A device of the class described, including a casing having an inlet port and an outlet port, a pair of coaxial disks mounted for rotation within said casing and having ring sections presenting spaced ends to form a pump chamber movable into and out of communication with said discharge port during the rotation of said disk, means for driving one of said disks at substantially uniform speed, means for imparting a variable speed to the other disk to vary the capacity of the pump chamber, said pump chamber having an inlet port through 110 one of said disks for communication with the inlet port of the casing, and means for controlling the inlet port of said pump chamber.

18. A device of the class described, including a casing having an inlet port and an outlet port, a pair of coaxial members mounted for rotation therein, said members having limited relative circumferential movement to effect liquid pumping action, 125 130

- means for driving one of said members, spring connections between said members normally tending to hold them in predetermined relative positions, the other of said members having a projection outside of said casing and a spring stop in the path of movement of said projection.
19. A device of the class described, including a casing having an inlet port and an annular row of outlet ports, a pair of coaxial members mounted for rotation therein, said members having limited relative circumferential movement to effect liquid pumping action, means for driving one of said members, spring connections between said members normally tending to hold them in predetermined relative positions, the other of said members having an annular row of projections outside of said casing, and a spring stop in the path of movement of said projections for effecting retardation of said last mentioned member at points corresponding in position to said outlet ports.
20. A device of the class described, including a casing having an inlet port and an annular row of outlet ports, a pair of coaxial members mounted for rotation therein, said members having limited relative circumferential movements to effect liquid pumping action, means for driving one of said members, spring connections between said members normally tending to hold them in predetermined relative positions, a star wheel secured to the other of said members, and a spring stop for engaging therewith and retarding said member a plurality of times during each revolution to effect relative movement of said members.
21. A device of the class described, including a casing having an inlet port and an annular row of outlet ports, a pair of coaxial members mounted for rotation therein, said members having limited relative circumferential movement to effect liquid pumping action, means for driving one of said members, spring connections between said members normally tending to hold them in predetermined relative positions, a star wheel secured to the other of said members, a spring stop for engaging therewith and retarding said member a plurality of times during each revolution to effect relative movement of said members, and means for varying the effective action of said spring stop to control the quantity of liquid discharged.
22. A device of the class described, including a casing having an annular row of discharge ports, a pair of coaxial members rotatable in said casing and having relative circumferential movement to effect pumping action through said ports, means for driving one of said members, a spring connection between said members normally tending to hold them in predetermined relative positions, a star wheel secured to the other member, a spring in the path of movement of said star wheel for stopping said last mentioned member a plurality of times during each revolution and in positions corresponding to said discharge ports.
23. A device of the class described, including a casing having an annular row of discharge ports, a pair of coaxial members rotatable in said casing and having relative circumferential movement to effect pumping action through said ports, means for driving one of said members, a spring connection between said members normally tending to hold them in predetermined relative positions, a star wheel secured to the other member, a spring in the path of movement of said star wheel for stopping said last mentioned member a plurality of times during each revolution and in positions corresponding to said discharge ports, and adjusting means for varying the effective action of said spring stop.
24. A device of the class described, including a casing having an annular row of discharge ports, a pair of coaxial members rotatable in said casing, a drive shaft secured to one of said members, a sleeve secured to the other member and a spring outside of the casing and connecting said shaft and sleeve to permit limited relative circumferential movement of said members, and thereby effect pumping action through said ports.
25. A device of the class described, including a casing having an annular row of discharge ports, a pair of coaxial members rotatable in said casing, a drive shaft secured to one of said members, a hand wheel secured to said shaft, a sleeve secured to the other member, a star wheel secured to said sleeve, a spring outside of said casing and connecting said hand wheel and said star wheel, and a spring for intermittently resisting the rotation of the star wheel.

Signed at New York, in the county of New York and State of New York, this 10th day of April, A. D. 1922.

ARTHUR W. THOMPSON.
